(57) **CLAIM**

The ornamental design for a work glove, as shown and described.

DESCRIPTION

FIG. 1 is a front view of a work glove showing my new design;

FIG. 2 is a rear view of the work glove;

FIG. 3 is a right side view of the work glove;

FIG. 4 is a left side view of the work glove;

FIG. 5 is a top view of the work glove;

FIG. 6 is a bottom view of the work glove; and,

FIG. 7 is a top front side perspective view of the work glove. The broken lines in FIG. 6 are illustrative of portions of the work glove forming no part of the claimed design. The applied stippling technique along the surfaces of the work glove represents a contrast in appearance and does not reflect a particular surface ornamentation or material.
